 N. J., a corporation of New Jersey

Application October 21, 1933, Serial No. 694,553

9 Claims. (Cl. 274—17)

This invention relates to phonographs, and more particularly to business phonographs which are primarily adapted and principally used for both recording and reproducing dictation.

5 Phonographs of this type commonly include a support adapted to bear and rotate a record tablet, and a carriage bearing suitable translating means and capable of motion simultaneously with, but in a direction transverse to that of, the motion of the adjacent record tablet surface. A selective control is provided over the function of the machine, adjustable to at least two positions. In one, the recordation position, it causes engagement with the tablet surface of translating means adapted to produce a record in such surface, upon rotation of the latter, of sound and particularly dictation transmitted into the phonograph. In another, the reproduction position, the control causes engagement with the tablet surface of translating means adapted to produce sound, upon rotation of the surface, in accordance with a record previously made therein. The selective control is usually (though for purposes of the instant invention not indispensably) adjustable to a third or neutral position, wherein it maintains all translating means out of engagement with the tablet surface, irrespective of rotation of the latter.

In order that a person transmitting dictation into the phonograph may not mistakenly dictate with the selective control adjusted to other than the recordation position, there are commonly provided means for producing a sustained signal—usually an intermittent, audible one—when and as the tablet (hereinafter conveniently referred to as the record, irrespective of its surface condition) is rotated under these circumstances. There are also commonly provided means for producing an essentially instantaneous signal when recordation is in progress and has approached the limit permitted by the record surface or by the available range of motion of the translating means; it being intended thereby to warn the dictator to cease his dictation pending change of the record in use or some other readjustment properly permitting continuance of dictation.

Conventionally these two signalling means are distinct. As contemplated by my invention, however, they are united in a single device with appropriate actuating means. Preferably this device produces a signal of sustained rather than instantaneous nature, not only for indicating lack of control adjustment to the recordation position, but also for indicating the approach of

the mentioned permissible limit in recordation. This has the material advantage of obviating failure of perception of the latter indication by the dictator, which frequently occurs in the case of the present instantaneous signal by reason of 5 momentary physical or mental distractions.

Thus it is broadly an object of my invention to provide, in a business phonograph, generally improved means for indicating to the dictator an absence of conditions appropriate to the recordation of his dictation.

It is a further object to provide in such a phonograph a signalling device actuated upon the occurrence of any of a plurality of conditions rendering the phonograph temporarily unsuited for recordation.

It is a still further object to provide in such a phonograph improved means for warning the dictator, both of an adjustment of the selective control to a position other than that for recordation and or the approach of the recordation process to a permissible limit.

Another object of my invention is the provision of more effective means for warning the dictator during recordation that this process has approached or reached the limit permitted by record surface or available translating means motion.

Other and allied objects will more fully appear from the following description and the appended 30 claims.

In the description reference is had to the accompanying drawings, of which

Figure 1 is a top plan view, with portions broken away, of a conventional form of business 35 phonograph in which my invention has been incorporated;

Figure 2 is an elevational view taken from the left hand end of the phonograph, a small portion of which is broken away in order better to illustrate certain interior members;

Figure 3 is a view generally similar to Figure 2, but restricted to portions forming parts of, or most immediately associated with, an embodiment of my invention;

Figure 4 is a fragmentary rear elevational view aiding in the description of Figures 1, 2, and 3;

Figures 5 and 6, the latter a sectional view taken along line 6—6 of the former, illustrate an embodiment of my invention modified in respect 50 of certain portions from that illustrated in preceding figures;

Figure 7 illustrates an embodiment of my invention wherein a visible signalling device is employed, and which is appropriately modified from 55

embodiments illustrated in the earlier figures; and

Figure 8 is a diagrammatic view of an electric circuit appropriate for use with the embodiment 5 of Figure 7.

In the drawings, particularly in Figures 1 and 2, so much of a typical business phonograph is illustrated as is necessary to show the connection of my invention therewith. Thus in these 10 figures there will be seen a mandrel 1 adapted to carry, and illustrated as carrying, a cylindrical record A. The shaft 2 of the mandrel is journaled in bearing 3, which is secured to the top plate 4 of the phonograph cabinet 8'. The mandrel 1 is adapted to be driven by pulley 5, which through the medium of stud 6 is rotatably mounted on standard 7. The pulley 5 is in turn driven through the medium of belt 8 by a motor (not shown) which may be encased in the cabinet 20 inset 8'.

The continuous rotation of pulley 5 is contemplated; and in order to afford instantaneous control over the rotation of mandrel 1 there is provided a selectively operable clutch including the 25 coating members 9 and 10. The member 9 is fastened to pulley 5, while the member 10 is splined on the shaft 2. For purposes of description of the instant invention it is sufficient to indicate a clutch control system by its terminal 30 member 11—a pivoted arm which engages an annular groove 12 in clutch member 10 and is adapted to move the latter into and out of engagement with the clutch member 9.

The translating means, which it is not herein 35 necessary specifically to show, are comprised within the unit 14 borne by the carriage 13. The latter is in the form of an arm provided with a boss 15 near the unit 14 and provided with a bifurcation 16 at its extremity. The boss 15 and 40 bifurcation 16 slidably engage front rod 17 and back rod 18, respectively, and permit motion of the carriage 13 and unit 14 in the longitudinal direction of these rods—i. e., in a direction parallel to the shaft 2 and thus transverse to that 45 of motion of the record surface immediately under the unit 14. The rods 17 and 18 are terminally supported by standards 7 and 7', which are secured to the top plate 4 near the left hand and the right hand ends thereof, respectively. 50 During either recordation or reproduction a steady motion of the carriage 13 along the rods, coincident with the rotation of mandrel 1, is positively produced by the engagement of the carriage-borne feed nut 20" with a feed screw 20, 55 which screw is geared to the shaft 2 through the screw-borne gear 22 and the shaft-borne gear 21, and is journaled on bearings 20' in standards 7 and 7'. This motion is unidirectional and is contemplated as taking place toward standard 60 7'; it is hereinafter referred to as the travel of the carriage (or unit) to distinguish it from random or other motion of the carriage effected independently of the feed screw 20.

The selective control for adjustment of the 65 phonograph at least for recordation and reproduction, respectively, and hereinabove mentioned, is shown as lever 25 protruding through slot 26 in the top of carriage 13, immediately above the boss 15. This lever is shown in Figure 1 adjusted 70 forwardly of the slot to the recordation ("dictate") position. It may however be adjusted to a neutral ("off") position by placement immediately of the slot extremities; or to the reproduction ("hear") position by placement rearwardly of the slot. It is contemplated that each 75

adjustment of the lever 25 causes an appropriate arrangement of translating means with respect to the record and that adjustment of the lever to the neutral position further may disengage the feed nut 20" from the feed screw 20, thus permitting free motion of the carriage 13 along the rods 17 and 18. The adjustment of the lever 25 may have further functions, certain of which are closely associated with my invention in its illustrated embodiments and are therefore specifically 10 described hereinafter.

The apparatus thus far described is wholly conventional, and forms a typical construction to which appropriate signalling or warning means are desirably applied. Means for signalling adjustment of the control 25 to other than recordation position and means for signalling proximity of the permissible limit in recordation have been illustrated and are described below; it is to be understood that each of such means broadly is 20 well known, but that my invention includes certain novel features in each as herein shown and described, and certain novel interrelations of the two means, which points of novelty are set forth 25 in the appended claims.

In the embodiments of my invention illustrated in the various figures of the accompanying drawings the warning or indicating means is contemplated as including a signalling device proper and an appropriate actuating system therefor. In 30 those embodiments illustrated in Figures 1 through 6 the signalling device is contemplated as a bell B, a hammer 32 adapted to strike the bell, and a resilient arm 31 carrying the hammer. The bell is conveniently carried by a vertical 35 bracket 28 secured to the top plate 4 and occupying a position closely adjacent the face of gear 22. The parts thus far mentioned are most easily seen in Figure 2.

In the embodiments of Figures 1 through 6 the 40 terminal portion of the signal actuating system is an angular trip lever 29 to which the arm 31 is secured. The trip lever may comprise the longer arm 29" and the shorter arm 29', and may be pivoted near the apex of its angle by 45 pivot screw 30 to the vertical face of bracket 28. The trip lever, principally dottedly illustrated in Figure 2, is best seen in Figure 3. Rotation limiting means for the lever 29 is provided in the 50 form of a lug 33 secured to or bent over from the vertical bracket 28 and occupying a horizontal position intercepting the plane of the trip lever; the sides 35 and 34 of a notch 33' formed in the end of the shorter lever arm 29', impinging upon the lug 33, respectively limit the counter-clockwise and clockwise rotation of the lever. In the absence of special forces hereinafter described 55 no particular angular position of the lever 29 is contemplated; it is illustrated in Figure 3, however, in its position of maximum counter-clockwise rotation, which for reasons hereinafter appearing may be termed its live position.

It will be seen that with the lever 29 in the described live position, the hammer 32 does not quite touch the surface of bell B. If, however, 65 the lever 29 be rotated slightly in a clockwise direction and then abruptly restored to live position—or in other words tripped—the signalling device will be operated, since the momentum acquired by the hammer before the completion of 70 the abrupt lever return will upon such completion cause the momentary flexing of resilient arm 31 and the striking of bell B by the hammer. The device for producing the abrupt return of the lever 29 to live position during tripping is identi- 75

cal with a portion of certain means hereinafter described; it comprises a coil spring 35' rigidly secured at one extremity, intermediately encircling the pivot screw 30, and terminally hooked 5 around the forward edge of the lever arm 29'', and urges the lever 29 to counter-clockwise rotation.

The other portions of the signal actuating system operate to trip the lever 29, when this is in 10 its live position, upon each rotation of the feed screw (and hence intermittently throughout rotation of the mandrel 1). These include a member 41, hereinafter referred to as the trip member. This extends essentially tangentially outward 15 from the surface of the feed screw 20; it may be provided with a resilient sleeve portion 40 clamped around the feed screw, and may conveniently be terminally secured to the hub 24 of screw-borne gear 22, as by set screw 23. In order 20 to obviate jamming under the possible circumstance of rotation of the feed screw in a counter-clockwise instead of the contemplated clockwise direction (as illustrated in Figures 2 and 3), it is desirable that in tripping the lever 29 the trip 25 member 41 do not engage a portion of, or be rigidly secured to, the lever itself. There has therefore been illustrated, most clearly in Figure 3, a latch 36 pivoted to the trip lever at the intermediate point 27 on the longer arm 29'', and 30 extending into the path of the trip member when the trip lever occupies its live position. When the trip member impinges upon the latch from the left, as in clockwise rotation of the feed screw, the latch presents to the trip member a surface 35 secure with respect to the trip lever; this results from the gravity-maintained engagement of the latch edge surface 36' with a lug 38 secured to or bent over from the edge of the trip lever. Thus upon each of its revolutions in the 40 contemplated direction the trip member, first impinging upon the latch, forces the trip lever to rotate slightly in a clockwise direction, and then disengaging the latch, suddenly releases the trip lever; this of course assumes the lever initially 45 in its live position.

The mode of operation of the signal actuating system having been described, attention may be directed to the means for controlling the system to provide operation at the desired times. As 50 initially mentioned in this specification my invention contemplates the use of the same signalling device for indicating a condition of adjustment of the control 25 to other than recordation position, and a condition of proximity of the permissible limit in recordation. The signal actuating system is therefore so controlled as to operate under each of these conditions. For purposes of description the control means may be separated into three portions: first, means responsive to 55 an adjustment of control 25 to other than recordation position; secondly, means responsive to a condition of proximity of carriage 13 to the permissible limit of its travel; and lastly, means connected with both the preceding means for placing 60 the actuating system in operation upon response of either such preceding means.

As the first of the three mentioned means I employ an arrangement heretofore utilized in signalling lack of adjustment of the selective 65 function control (25) to recordation position. Thus the front rod 17 is mounted to the standards 7 and 7' in manner permitting its rotation therein. In the bottom of the rod 17 is provided a longitudinal groove or spline 17' engaged by a key 25', the key being secured in the hub 25'' of

the lever 25. Motion of the control lever 25 therefore rotates the rod 17 and provides a different angular position thereof for each of the three contemplated control lever adjustments. To the end of rod 17 may be secured, as by screw 66, an 5 arm or crank 65, which will be understood to respond to adjustment of control 25 by assuming three respective positions.

As the second of the three mentioned means I employ an arrangement for rotating the rod 10 18 under appropriate conditions, and an arm or crank 68 secured, as by screw 69, to the end of the rod. In this arrangement the rod 18 is rotatably mounted in the standards 7 and 7', being prevented from executing longitudinal movement 15 as by the key 55 in standard 7 engaging a partial annular groove 56 in the rod.

In considering the means whereby the rod 18 is rotated, it is necessary to observe that Figures 1 through 4 illustrate one modification of such 20 means, and Figures 5 and 6 another. In the first group of figures there is shown secured to the rod 18 near the standard 7' a split collar 53, as by set screw 54. An urge to counter-clockwise rotation is at all times imparted to the rod 18 (as 25 shown in Figures 2 and 3) by a torsion spring 57 terminally secured to standard 7' and split collar 53, respectively. Normally this urge is resisted and a definite angular position of rod 18 is established by engagement of the key 55 with an 30 extremity of the partial annular groove 56. Depending from the collar 53 is provided a finger 52. This finger lies in the path of a cam surface 51 on the right hand end of a lug 50, secured to the carriage 13 under its bifurcation 16. Upon engagement of the finger 52 by the cam surface 51 and motion of the surface past the finger, the latter is pushed rearwardly to rotate the rod 18 in a clockwise direction from its original position by an amount which may conveniently be about 35 25 degrees. In this structure, while the rod 18 is positively moved in the clockwise direction, the torsion spring 57 is relied on to return rod 18 in a counter-clockwise direction to its original angular position upon movement of the carriage 40 45 disengaging the lug 50 and finger 52. In the modification illustrated in Figures 5 and 6, however, the rod 18 is positively moved in both directions. Herein a longitudinal groove or spline 71 is provided along the bottom of rod 18. This 50 groove is provided with an offset of about 25 degrees at a point corresponding longitudinally to the point in the earlier figures occupied by the center of the bifurcation 16 at the time of engagement of cam 51 and finger 52. Projecting 55 from the center of the lower portion of the bifurcation 16 into the groove 71 is provided a key 70. The engagement of the key with the main portion of the groove maintains the rod 18 in a normal angular position, and the motion of the key 60 from the main portion through the offset 72 produces clockwise rotation of the rod, the direction of offset being appropriately chosen thereto. Return of the key 70 through the offset to the main portion of the groove of course provides a positive 65 return of rod 18 to its original angular position. It will be understood that either of these two modifications will be arranged to produce the rotation of rod 18 from its normal angular position when the unit 14 has approached the 70 permissible limit of its travel and that the arrangements inherently maintain the rod in its rotated position until the carriage 13 and unit 14 have been deliberately moved to a more leftward position. The crank 68 will therefore be seen to 75

be responsive by a small clockwise change of position, to a condition of proximity of carriage 13 and unit 14 to the permissible limit of their travel.

5 As the third of the three mentioned means I employ the already mentioned spring 35' which urges the trip lever 29 into live position; a rod 60 secured to and extending leftwardly from the arm 29' of the trip lever; and a rod-like member 62 10 pivoted as at 61 to an extremity of crank 68, having a bifurcation 63 at its opposite extremity engaging a stud 64 secured to the extremity of crank 65, and having a dependent arm 61. The member 62 and parts associated therewith are 15 so arranged that with the rear rod 18 in approximately the middle of its small range of rotation the member 62 is essentially at right angles to crank 68, whereas with the front rod 17 in the central of its three positions of adjustment the member 62 is in substantial alignment with the crank 65.

The arm 61 is adapted at times to engage and support the rod 60; these times are those at which the phonograph is in a condition properly 25 permitting continued dictation. The arm 61 then maintains the rod 60 in an elevated position and hence the trip lever arm 29' in a position forward of its live position; under these circumstances the trip lever is in a dormant position, 30 maintaining latch 36 out of the path of the trip member 41. Thus when crank 68 occupies the most counter-clockwise position in its small rotation range and the crank 65 occupies the most clockwise of its three positions (corresponding 35 to a position of the carriage not close to the permissible limit of its travel and to an adjustment of the control 25 for recordation) the arm 61 will maintain the rod 60 in the mentioned elevated position. These conditions are indicated 40 dottedly in Figure 2.

At other times—those which are appropriate to the operation of the signalling device—the dependent arm 61 is lowered and withdraws its support of rod 60, whereupon the spring 35' urges 45 the trip lever 29 to its live position. Thus when crank 68 occupies its most clockwise position and crank 65 occupies the most clockwise of its three positions (corresponding to a position of the carriage close to or at the permissible limit of its travel and to an adjustment of the control 25 50 for recordation, and as illustrated in Figure 3) the arm 61 will be out of contact with or will just touch rod 60; when crank 68 is at any position within its range and crank 65 occupies the central 55 of its three positions (corresponding to a neutral adjustment of the control 25, and as illustrated in full in Figure 2) the arm 61 will be out of contact with or will just touch rod 60; and when crank 68 is at any position within its range 60 and crank 65 occupies the most counter-clockwise of its three positions (corresponding to an adjustment of the control 25 for reproduction) the arm 61 will be wholly out of contact with the rod 60.

65 The third of the three mentioned means having been thus described, it will be apparent that it places the signal actuating system in operation upon the response, as above defined, of either of the first two mentioned means. It will further 70 be apparent that when actuated the signalling device produces an intermittent signal and that it does so only during mandrel rotation—i. e., when the clutch 9—10 is engaged. Slightly modified results are produced in the operation of the embodiment of my invention illustrated in Figures 75

7 and 8, wherein visible instead of audible signalling means are illustrated.

The general construction shown and described in and in connection with Figures 1 and 2 is assumed in this further embodiment. There are 5 omitted, however, bell B, trip lever 29, trip member 41, and parts immediately associated with and incidental to the operation of these elements; and the member 62 with its arm 61 is replaced by a somewhat different member. The signalling device is shown as lamp 86, which may be mounted on the speaking tube 87 dottedly illustrated in Figure 2 or in any other prominent location. It may be connected by leads 88 to a plug 99, illustrated as a female plug and adapted to connect the leads 88 to the prongs 94 and 94' provided as external contacts on a switch casing 80. Included in the switch casing is a switch 82; this comprises a contact spring 84 connected to prong 94, a second contact spring 83 connected 20 to prong 94', and a contact member 81 adapted to close the switch by impinging upon and electrically connecting the contact springs 83 and 84. The prong 94' and the contact spring 83 may be connected by leads 94'' and 85, respectively, 25 across the motor 93 which drives the pulley 5 through the medium of belt 8 (Figure 1). The symbols 90 and 92 respectively designate a source of power for the motor and a switch controlling the motor operation; these are connected in series with the motor. Obviously the closing of switch 92, supplying power to the motor, will also supply power to the circuit 85—83—84—94—88—94—94'', which may be considered the signal 30 actuating system. 35

In Figure 7 the switch casing is shown conveniently secured to the standard 7. The casing is provided with a boss 79, and within this boss may operate plunger 78 carrying at its lower extremity the contact member 81 already referred 40 to as part of the switch 82. When plunger 78 occupies its raised position as shown in Figure 7, the switch 82 is obviously open; but plunger 78 is adapted to be lowered to close switch 82, and thus forms part of the means for placing the signal actuating system in operation, the balance of which means is described in the following paragraph. As in the case of the embodiments hereinabove described, this means performs its function when either of the cranks 65 and 68 has responded to the conditions intended to be signalled. 45

Thus to the upper extremity of the plunger 78 may be pivoted, as at 77', a link 77, and the link may in turn be pivoted as at 77' to an intermediate point on the rod-like member 75. At one 55 extremity the member 75 is pivoted to the extremity of crank 68, as by pivot stud 67; at the other extremity it is provided with a bifurcation 100 engaging the stud 64 secured to the extremity of crank 65. The general arrangement of the 60 member 75 with respect to the cranks 65 and 68 is similar to that of the member 62 in previously described embodiments. Its function in cooperation with link 77 and plunger 78 may be most easily described as follows:—

When the crank 68 occupies the most counter-clockwise position in its small angular rotation range and the crank 65 occupies the most clockwise of its three positions (corresponding to a condition appropriate for continued recordation and 70 as illustrated in full in Figure 7) the plunger 78 occupies a raised position as shown and the switch 82 is open. If the crank 68 be rotated to the most clockwise position in its range the member 75 75 will be displaced rearwardly and downwardly, 75

- lowering plunger 78 and contact 81 sufficiently to close switch 82. On the other hand, and independently of the position of crank 68, if the crank 65 be rotated in a counter-clockwise direction to either its central or extreme counter-clockwise positions, the member 75 will swing downwardly about its pivot in a clockwise direction (as illustrated) and will lower plunger 78 and contact 81 at least sufficiently to close switch 82.
- 10 In previously described embodiments and in this embodiment as thus far described, no differentiation of signal nature in accordance with the condition signalled is effected; the present embodiment as thus far described produces a steady 15 lighting of the lamp 86 as long as the control 25 is adjusted to other than recordation position and produces a similar effect whenever the carriage 13 is close to the permissible limit of its travel. To provide a differentiation of nature between signals respectively indicating these two 20 conditions, I have provided a means for intermittently opening the switch 82 when it would be otherwise maintained steadily closed in response to the second of these conditions. Thus 25 the member 75 is provided, at its point of pivoting to the crank 68, with an elongated slot 95, the arrangement being such that the pivot stud 67 may in the absence of special forces occupy any position between the extremities of the slot. A spring 30 96, however, is secured to the member 75 as at 77' and to the pivot stud 67, and normally maintains the pivot stud in engagement with the forward extremity of the slot. The member 75 is further provided near its forward extremity with 35 a projection 97 extending downwardly in front of the feed screw 20; the projection 97 being curved inwardly at 97' to bring its lower portion within the space between the standards 7 and 7'. Suitably secured to the feed screw 20 opposite 40 the projection 97 is provided a cam member 98 having cam portion 98'. As long as the crank 68 occupies the most counter-clockwise position in its small angular range the projection 97 lies outside the rotary path of the cam portion 98', no 45 matter which of its three positions is occupied by crank 65. When the crank 68 is moved to its most clockwise position, however, the resulting rearward displacement of the member 75 brings the projection 97 into the path of the cam surface, 50 which upon each of its revolutions will force the projection, and hence the entire member 75, to move forwardly against the force of spring 96 (as is permitted by the slot 95) and the plunger 78 consequently to rise. If the switch 82 has been 55 closed solely by virtue of the clockwise position of crank 68—i. e., if crank 65 remains in its most clockwise position, as shown in Figure 7—the intermittent rising of the plunger 78 will be of sufficient degree intermittently to open switch 60 82, and the signalling device is therefore intermittently rather than steadily actuated. It will be noted that this intermittent actuation occurs only when the carriage is closed to its permissible travel limit during recordation; when the control 65 25 is otherwise adjusted than for recordation the steady actuation of the signalling device occurs irrespective of the position of the carriage.
- I call particular attention to the fact that the signal produced by any of the embodiments of my invention to indicate proximity of the carriage to its permissible limit of travel, is a sustained signal, whether intermittent or steady; and to the fact that it continues until the carriage is deliberately moved in a leftward direction.
- 70 75 This has the dual advantages over a momentary

warning signal both of insuring observation of the signal by the dictator, and of warning him of the continuance of conditions inappropriate to recordation if he changes a completed record without returning the carriage to the initial or an intermediate point in its range of travel.

It is to be understood that I do not intend to limit my invention by the specific details illustrated and described for explanatory purposes, but rather intend to express the scope of the invention in the following claims.

I claim:—

1. In a phonograph having both recording and reproducing functions, including translating means adapted to cooperate with a rotated record, 15 and including record rotating means and coacting means for moving said translating means in a determinate path: the combination of means selectively adjustable to control the function of said phonograph; means responsive to the presence of 20 said translating means only within a definite predetermined portion of said path; a signalling device; means for actuating said signalling device; and means comprising a device connected with and influenced by both said selective means and 25 said responsive means for controlling the operation of said actuating means.

2. In a phonograph having both recording and reproducing functions, including translating means adapted to cooperate with a rotated record, 30 and including record rotating means and coacting means for moving said translating means in a determinate path: the combination of means controlling the function of said phonograph and selectively adjustable to recordation and further 35 positions; mean responsive to the presence of said translating means only within a fixed terminal portion of said path; a signalling device; means for actuating said signalling device; and means comprising a device connected with and influenced by both said selective means and said responsive means for controlling said actuating means to provide actuation of said signalling device only under either of the conditions of presence of said translating means within said fixed 40 path portion, and of adjustment of said selective means to any of said further positions.

3. In a phonograph having both recording and reproducing functions, including translating means adapted to cooperate with a rotated record, 50 including record rotating means and coacting means for moving said translating means in a determinate path, and including function control means selectively adjustable to recordation and further positions: the combination of means responsive to an adjustment of said function control means to any of said further positions; means responsive to the presence of said translating means within a fixed terminal portion of said path; a device for producing a signal; means controlled by both of said responsive means for actuating said signalling device during response of either of said responsive means; and means associated with said actuating means and adapted to so influence the same as to differentiate the nature of the signal produced during the sole response of a predetermined one of said responsive means from that produced during response of the other, said associated means comprising a part 55 which is movable by one of said responsive means to and from a position wherein it renders such associated means operative to influence said actuating means as described.

4. In a phonograph having both recording and 75

reproducing functions, including translating means adapted to cooperate with a rotated record, including record rotating means and coacting means for moving said translating means in a determinate path, and including function control means selectively adjustable to recordation and further positions: the combination of means responsive to an adjustment of said function control means to any of said further positions; means responsive to the presence of said translating means within a fixed terminal portion of said path; a device for producing a signal; means controlled by both of said responsive means for actuating said signalling device during response of either of said responsive means; and means associated with said actuating means and adapted to so influence the same as to modify the nature of the signal produced during the sole response of a predetermined one of said responsive means, said associated means comprising a part which is movable by the said predetermined one of the responsive means to and from a position wherein it renders such associated means operative to influence said actuating means as described.

5. In a phonograph having both recording and reproducing functions, including translating means adapted to cooperate with a rotated record, including record supporting means, means for rotating said supporting means and coacting means for moving said translating means in a determinate path transverse to the direction of record rotation, and including function control means selectively adjustable to recordation and further positions: the combination of means responsive to an adjustment of said function control means to any of said further positions; means responsive to the presence of said translating means within a fixed terminal portion of said path; a device for producing an audible signal and actuating means therefor adapted for operative association with said record supporting means for intermittent energization during rotation of said supporting means; and means connected with both of said responsive means and comprising a movable device associated with said actuating means for controlling the operation thereof, said device being movable under the influence of both of said responsive means to a position in which the operation of said actuating means is effected to provide intermittent actuation of said signalling device only during response of at least one of said responsive means.

6. In a phonograph having both recording and reproducing functions, including translating means adapted to cooperate with a rotated record, including record rotating means and coacting means for moving said translating means in a determinate path transverse to the direction of record rotation, and including function control means selectively adjustable to recordation and further positions: the combination of means responsive to an adjustment of said function control means to any of said further positions; means responsive to the presence of said translating means within a fixed terminal portion of said path; an electric circuit including a lamp and actuating means therefor; a switch serially connected in said circuit; and means connected with and influenced by both of said responsive

means for closing said switch, to provide actuation of said lamp during response of either of said responsive means.

7. In a phonograph having both recording and reproducing functions, including translating means adapted to cooperate with a rotated record, including record rotating means and coacting means for moving said translating means in a determinate path transverse to the direction of record rotation, and including function control means selectively adjustable to recordation and further positions: the combination of means responsive to an adjustment of said function control means to any of said further positions; means responsive to the presence of said translating means within a fixed terminal portion of said path; an electric circuit including a lamp and actuating means therefor; a switch serially connected in said circuit; means connected with and influenced by both of said responsive means for closing said switch, to provide actuation of said lamp during response of either of said responsive means; and means operative to effect intermittent interruption of said circuit and rendered thus operative solely upon the response of a predetermined one of said responsive means.

8. In a phonograph having both recording and reproducing functions, including translating means adapted to cooperate with a rotated record, and including record rotating means: the combination of two rods disposed in parallel relation to each other and transversely of the direction of record rotation; a carriage slidably engaging said rods and carrying said translating means; function control means selectively movable to recordation and further positions, said control means being borne by said carriage and engaging a first of said rods to control the angular position thereof; rod-rotating means jointly associated with said carriage and the second of said rods, for controlling the angular position of the latter rod in response to the position of said carriage longitudinally of said rods; a signalling device and means for actuating the same; and means connected with both said rods and influenced by the angular position of each for controlling said actuating means.

9. In a phonograph including translating means adapted to cooperate with a rotated record and including record rotating means: the combination of a rod disposed transversely of the direction of record rotation; a carriage slidably engaging said rod and carrying said translating means; means coacting with said record rotating means for producing unidirectional travel of said carriage along said rod; means normally maintaining said rod in a given angular position; means jointly associated with said carriage and said rod for rotating said rod to a displaced angular position only as said carriage in said travel passes a predetermined point on said rod; and for maintaining said rod in said displaced angular position only while said carriage remains beyond said point; a signalling device and actuating means therefor; and means connected with said rod and influenced by the angular position thereof for controlling said actuating means, to provide actuation of said signal while said rod occupies its displaced angular position.

LOUIS Z. LA FOREST.
